United States Patent Office.

ISAAC APPLIN SHEPPARD, OF PHILADELPHIA, PENNSYLVANIA.

Design No. 4,319, dated August 30, 1870.

DESIGN FOR THE PLATES AND DOORS OF A COOKING-STOVE.

The Schedule referred to in these Letters Patent and making part of the same.

I, ISAAC APPLIN SHEPPARD, of Philadelphia, county of Philadelphia, State of Pennsylvania, have invented or produced a Design for the Plates and Doors of a Cook-Stove, of which the following is a specification.

The figure in the accompanying drawing represents one of the side plates of a cook-stove, ornamented in accordance with my design.

The side plate has extending round it a molding, *a*, and each of the doors *A*, *B*, and *C* is ornamented by a heavier molding, *b*, of the character represented in the drawing.

In the center of the oven-door *A* there is an elaborate ornament, *e*, and the doors *B* and *C* have also central ornaments *f*, but of a character differing from the ornament *e*.

On the side plate, above the oven door, there is a panel, *h*, and extending beneath the oven-door and door *C* there is a panel, *i*, having rounded ends, as shown.

I claim—

The design for the plates and doors of a cook-stove, substantially as described and as illustrated in and by the accompanying drawing.

In testimony whereof I have signed my name to this specification in the presence of two subscribing witnesses.

ISAAC APPLIN SHEPPARD.

Witnesses:—

WM. A. STEEL,
HARRY SMITH.
